(57) **CLAIM**

The ornamental design for a wire duct, as shown and described.

DESCRIPTION

FIG. 1 is a front view of the design according to one embodiment of the invention.

FIG. 2 is a rear view of the design according to one embodiment of the invention.

FIG. 3 is a top view of the design according to one embodiment of the invention.

FIG. 4 is a bottom view of the design according to one embodiment of the invention.

FIG. 5 is a left side view of the design according to one embodiment of the invention.

FIG. 6 is a right side view of the design according to one embodiment of the invention.

FIG. 7 is an expanded cross-sectional view of the design cut along the A—A line of FIG. 3; and,

FIG. 8 is a perspective view of the design according to one embodiment of the invention.

1 Claim, 5 Drawing Sheets
